UNITED STATES PATENT OFFICE.

GOTTHILF ANSGARIUS BETULANDER, OF SÖDERTÖRNS VILLASTAD, AND NILS GUNNAR PALMGREN, OF STOCKHOLM, SWEDEN, ASSIGNEES TO THE RELAY AUTOMATIC TELEPHONE COMPANY, LIMITED, OF STRAND, LONDON, ENGLAND.

CALL-DISTRIBUTING ARRANGEMENT FOR TELEPHONE PLANTS.

1,375,351.

Specification of Letters Patent. Patented Apr. 19, 1921.

Application filed November 23, 1920. Serial No. 426,044.

To all whom it may concern:

Be it known that we, GOTTHILF ANSGARIUS BETULANDER and NILS GUNNAR PALMGREN, subjects of the King of Sweden, and residing at, respectively, Södertörns Villastad, Sweden, and Varvsgatan 14, Stockholm, Sweden, have invented a new and useful Improvement in Call-Distributing Arrangements for Telephone Plants, of which the following is a specification.

The invention relates to telephone systems, particularly automatic or semi-automatic systems, in which the subscribers' lines or the junction lines over which the talking connections are established are divided into groups which are served by switching devices common to all the lines in each group. In such systems means must generally be provided for insuring that the different calls shall be successively dealt with even when several calls simultaneously reach the switching device in question, for the purpose of preventing double connections or disturbances in the connecting operations. The different lines are then provided with relays or like switching devices which, during the switching operation, mark the line to be connected in a particular way, so that only this line obtains connection with the line in question or the common switching device. When two or more calls occur simultaneously there must be means for preventing more than one of said marking relays being brought into operation or remaining in the operated position. Systems are known in which this is attained by said relays mutually controlling their circuits so that, on operating, they mutually disconnect each other, only one of the relays being thus capable of keeping its armature attracted. In such an arrangement, however, the circuits of the different marking relays will include on an average a relatively large number of contacts connected in series, and this number increases with the number of lines and marking relays whereby the reliability of the service is diminished. The object of the present invention is to provide a call distributor arrangement which insures the successive connection of simultaneously calling lines and which is simpler and more reliable than the known arrangement above mentioned. The invention chiefly consists in that the lines and

the appertaining marking relays are divided into a plurality of groups, the marking relays which control the circuits of one another group-wise by the different relay groups, being provided with group marking relays which are brought into operation when a call occurs in the appertaining group and which control the circuits for the different groups of individual marking relays in such a manner that when calls occur simultaneously in different groups only one marking relay in one of said groups can operate or be kept in its operated position. The arrangement is preferably such that the common circuit of each group of marking relays is carried over back contacts in series of the group relays of all those groups which are connected to the source of current at points between the group in question and the source of current. By such a mutual group control of the circuits of the marking relays a considerable reduction of the number of contacts in said circuits and a corresponding simplification of the circuits is attained.

In order to prevent the simultaneous marking of a plurality of calls within the same group any suitable known means may be used. Preferably, however, a distributing arrangement may be used based on the above mentioned principle for a group control of the circuits of the marking relays. If the number of lines or marking relays is the same in the different groups, the marking relays corresponding to each other in the different groups may be put together to form secondary groups which similarly with the groups first mentioned, preferably called primary groups, are provided with secondary group relays so arranged as to be brought into operation, when a call occurs in the appertaining secondary group, said secondary group relays controlling the circuits of the different secondary relay groups in a similar way as the primary group relays control the circuits of the primary relay groups. In this way the circuits are further simplified and the number of contacts is further reduced.

The invention is illustrated by the accompanying drawings, in which Figures 1, 2 and 3, show schematically three different forms of the invention.

In the circuit arrangement shown in Fig.

1, LR¹, LR², LR³, designate line relays belonging to different talking lines not shown in the drawing, said relays being operated in a known manner when a call occurs on the appertaining line. MR¹, MR², MR³, designate corresponding marking relays which are likewise brought into operation upon a call occurring on the corresponding line. The circuits of said marking relays, 5 however, are arranged according to the invention in such a way that only one out of a plurality of simultaneously calling lines can be marked as calling. The lines and the appertaining relays are arranged in groups 10 G¹, G², G³, and the groups G¹ and G² are provided with group cut off relays GR¹ and GR² respectively. The different marking relays MR in each group G are jointly connected at one side to one pole (earth) of the 15 battery B over back contacts K¹, K², of the marking relays, and at the other side to the other pole of the battery over back contacts K³, K⁴, of the group relays, the arrangement being such that the circuit of each 20 marking relay is carried over back contacts connected in series of all marking relays of the same group connected between this relay and the pole in question of the battery, whereas the common circuit for the marking 25 relays in each group is carried over back contacts of the group relays of all relay groups connected between this relay group and the opposite pole of the battery.

Upon a call occurring for instance on the 30 third line of the group G² the corresponding line relay LR³ is energized whereby a circuit 1 is completed through the corresponding marking relay MR³. The latter energizes and closes a circuit 2 through the group 35 relay GR² which then operates yet without any other effect than that the relay group G³ is cut off. If two or more calls occur simultaneously in the same group only that marking relay MR which is next to the earth-connected pole of the battery will evidently 40 remain in operated position, as this relay cuts off the marking relays located to the right of the same, at its contact K¹ or K² respectively. If LR² and LR³ are thus 45 operated simultaneously, only MR² remains operated and only the appertaining line is marked. After completed connection of this line the appertaining relay LR² is energized, whereby MR² is caused to 50 energize and to complete the circuit 1 of MR³ which now effects the connection of the appertaining line. In case calls should occur simultaneously in two different groups, for instance on the third lines of 55 the groups G¹ and G², partly said circuit 1 and partly a circuit 3 are closed whereby both relays MR³ are energized simultaneously closing partly the circuit 2 through GR² and partly a circuit 4 through GR¹. 60 The relay GR¹ then opens the circuit of the 65

relay MR³ of the group G² which latter relay in turn opens the circuit 2 of the relay GR². Thus only the line in the group G¹ is marked as calling, i. e., generally only that line that belongs to the group which with 70 respect to the connection of the marking relays to the battery is located next to the latter. Should calls occur simultaneously in the groups G² and G³ the group G³ is similarly disconnected. 75

In the arrangement so far described no regard has been paid to the fact that two calls may enter immediately after one another so as to cause disturbance in the connecting operation started by the first call. 80 This drawback is eliminated in the arrangement shown in Fig. 2 by each call causing a disconnection of all marking relays except that one belonging to the calling line, which relay connects itself into a holding circuit. 85

Fig. 2 shows the invention as applied to the pre-selecting section of an automatic or semi-automatic telephone exchange. L¹ to L⁴ are subscribers' lines entering the pre-selecting section and FL¹ to FL³ are the 90 junction lines extending from this switching section, the connection with the latter being effected automatically on removing the telephone by means of a testing device S which is common to a group of, for instance, 95 100 subscribers' lines and which on being brought into operation tests the outgoing junction line and sends a current through a connecting relay AR corresponding to a disengaged line, said connecting relay connecting the calling line to this junction line. In the example shown in the drawing the connection is effected by means of a switching device in which said connecting relays AR and the marking relays MR allotted to the 105 subscribers' lines form operating and selecting electromagnets respectively and in which the connection is effected by energizing partly the selecting magnet (the relay MR) corresponding to the subscriber's line 110 and partly the operating magnet (the relay AR) corresponding to the junction line in question, the selecting magnet HL effecting such a mechanical marking of the series of contact sets KG corresponding to the subscriber's line that should the operating magnet AR operate owing to another call, only the contact set capable of establishing the 115 desired connection is operated.

LR and UR are the ordinary line and cut 120 off relays.

The subscribers' lines and the appertaining relays are divided into groups of, for instance, 10 lines.

The drawing shows complete circuits for 125 only one such group with the appertaining group relay GR³. The mutual connection of these groups appears from the connection represented by dotted lines and comprising the group relays GR² and GR¹ for two other 130

groups. The testing device S consists of a number of testing relays PR corresponding to the different junction lines, which testing relays are connected to the test wires d of 5 the junction lines by means of the group relays GR.

If a call occurs, for instance, on the third line of the third group, a circuit 5 is first closed over the line and the line relay LR³. 10 The latter energizes and closes a circuit 6 through the marking relay MR³ over series connected contacts on all group relays GR and through a relay IR. The marking relay MR³ energizes and connects itself into 15 a holding circuit 7 containing the group relay GR³ and extending over back contacts of all group relays connected between this group relay and the battery B. GR³ cuts in all testing relays PR to the corresponding 20 test wires, those testing relays which correspond to disengaged junction lines then receiving a current impulse. The testing relay; however, which is next to the battery opens the under test circuits as is seen from 25 the drawing, only the test circuit corresponding to this relay, for instance, the circuit 8, remaining closed. This circuit contains an operating winding AL of the relay AR² and this relay therefore energizes connecting itself into a circuit 9 and establishing 30 connection between the subscriber's line and the junction line in question over the contact set K³ G². A circuit 10 is then closed through the cut off relay UR³ and the holding winding HL of the relay AR² over the 35 third wires C¹ and C². The relay UR³ opens the circuit 5 of the line LR³ which in turn opens the circuit 7 of the marking relay MR³ and the group relay GR³ whereby the 40 testing device S is disconnected and the switching operation finished.

If calls should occur simultaneously in two different groups, for instance, the third and the second groups, the corresponding 45 marking relays energize simultaneously and the group relays GR³ and GR² receive a current impulse simultaneously. The relay GR² then, however, opens the holding circuit of the marking relay in the first group 50 and at the same time also the operating circuit of this relay so that the latter after having been deenergized cannot again energize. Thus, only the marking relay of the calling line in the second group remains operated. 55 A call occurring immediately after another call and when the operation for connecting the first calling line is going on cannot therefore operate the appertaining marking relay until after the connection of the said 60 line has been completed as the operating circuits of all marking relays are disconnected at the group relay in question as long as the connecting operation is going on.

In this arrangement other means are provided for preventing a simultaneous mark-

ing of more than one call if two or more calls should occur simultaneously in the same group. In such a case the marking relays will at first energize, however, as these relays then receive only half the current or even still less of the current passing through the group relay and the relay IR, they cannot keep their armatures attracted but release them. As, however, the self-induction and therefore the time in which a relay releases its armature is never exactly the same for two relays, one of the relays will release its armature before the other, its corresponding operating circuit being then again closed, so that the relay again energizes before the operating circuit of the other relay is yet closed. The corresponding group relay then opens the operating circuit and the relay last mentioned can therefore no longer be operated until the connection of the first marked line has been completed.

Fig. 3 shows a still more simplified circuit arrangement in a representation similar to the arrangement according to Fig. 1. 90 The arrangement for preventing a simultaneous marking of calls in different groups and for preventing disturbances by calls following immediately after one another is the same as in Fig. 2. For preventing a simultaneous marking of several calls in the same group, however, the following means are provided:—The different groups G¹, G², G³, have an equal number of lines and marking relays and the relays in the different groups 100 which correspond to each other are put together in groups SG¹, SG², SG³, which as distinguished from the first mentioned primary groups will be called secondary groups. These groups are provided with 105 secondary group relays SGR¹, SGR², SGR³, which correspond to the primary group relays, inasmuch as they control the operating circuits for the marking relays, so that the simultaneous marking of a plurality of 110 calls in different secondary groups, i. e. in the same primary groups, is prevented. For this purpose all marking relays of each secondary group are jointly connected to the positive pole (earth) of the battery over series connected back contacts K⁵, K⁶, K⁷, of the group relays of all secondary groups connected between the group in question and said pole of the battery. The secondary group relays are preferably included in the 115 circuit common to all marking relays in the corresponding secondary group.

If two or more calls occur simultaneously in the same primary group, i. e. in different secondary groups, it is evident that only one 125 of the secondary group relays can remain in its operated position and consequently only the corresponding line is marked as calling. When calls occur simultaneously in several primary groups, the switching 130

operation is controlled by the primary group relays GR^1 , GR^2 , GR^3 , in the same manner as in the arrangement according to Fig. 2.

5 Evidently the invention is not restricted to the use of relays of the kind described but other apparatus operating in a similar way may be used.

What we claim is:

10 1. In means for effecting the successive connection of simultaneously calling telephone lines, the combination of a number of lines, a number of relays adapted to mark corresponding lines as calling, the lines and relays being divided into a plurality of groups, a group relay allotted to each group and adapted to operate upon a call occurring in its group and means adapted upon such group relay operating to prevent more than 15 one of the marking relays from remaining operated.

2. In means for effecting the successive connection of simultaneously calling telephone lines, the combination of a number of lines, a number of relays adapted to mark corresponding lines as calling, the lines and relays being divided into a plurality of groups, a group relay allotted to each group and adapted to operate upon a call occurring in its group, a source of current 25 adapted to energize the relays, and a circuit for each group of marking relays carried over series connected back contacts of the group relays of the groups connected between its own group and the source of current.

3. In means for effecting the successive connection of simultaneously calling telephone lines, the combination of a number of lines, a number of relays adapted to mark corresponding lines as calling, the lines and relays being divided into a plurality of groups, a group relay allotted to each group and adapted to operate upon a call occurring 40 in its group, the marking relays which correspond to each other in the different groups being divided into secondary groups, a secondary group relay allotted to each secondary group and adapted to operate 45 upon a call occurring in its secondary group, and a source of current, the marking relays of each secondary group being jointly connected to the source of current over series connected contacts of the secondary group relays of all relay groups connected between the secondary group in question and the source of current.

4. In means for effecting the successive connection of simultaneously calling telephone lines, the combination of a number of lines, a number of relays adapted to mark corresponding lines as calling, the lines and relays being divided into a plurality of groups, a group relay allotted to each group 55 and adapted to operate upon a call occurring in its group, the marking relays which correspond to each other in the different groups being divided into secondary groups, a secondary group relay allotted to each secondary group and adapted to operate upon a call occurring in its secondary group, and a source of current, the marking relays being connected in each secondary group to one pole of the source of current over contacts of the secondary group relays and in each primary group to the opposite pole of the source of current over contacts of the primary group relays.

5. In means for effecting the successive connection of simultaneously calling telephone lines, the combination of a number of lines, a number of relays adapted to mark corresponding lines as calling, the lines and relays being divided into a plurality of groups, a group relay allotted to each group and adapted to operate upon a call occurring in its group, the marking relays which correspond to each other in the different groups being divided into secondary groups, a secondary group relay allotted to each secondary group and adapted to operate upon a call occurring in its secondary group, and a source of current, the marking relays being connected in each secondary group to one pole of the source of current over contacts of the secondary group relays and in each primary group to the opposite pole of the source of current over contacts of the primary group relays.

6. In means for effecting the successive connection of simultaneously calling telephone lines, the combination of a number of lines, a number of relays adapted to mark corresponding lines as calling, the lines and relays being divided into a plurality of groups, a group relay allotted to each group and adapted to operate upon a call occurring in its group, the marking relays which correspond to each other in the different groups being divided into secondary groups, a secondary group relay allotted to each secondary group and adapted to operate upon a call occurring in its secondary group, and a source of current, the marking relays being connected in each secondary group to one pole of the source of current over contacts of the secondary group relays and in each primary group to the opposite pole of the source of current over contacts of the primary group relays, the secondary group relays being included in the circuit common to all marking relays of the appertaining secondary group.

6. In means for effecting the successive connection of simultaneously calling telephone lines, the combination of a number of lines, a number of relays adapted to mark corresponding lines as calling, the lines and relays being divided into a plurality of groups, and a group relay allotted to each group and adapted to operate upon a call occurring in its group, each group relay being adapted upon energizing to put all marking relays except that one belonging to the calling line in question, which remains energized, out of operation.

7. In means for effecting the successive connection of simultaneously calling telephone lines, the combination of a number of lines, a number of relays adapted to mark corresponding lines as calling, the lines and relays being divided into a plurality of groups, a group relay allotted to each group and adapted to operate upon a call occurring in its group, a source of current and a holding circuit common to all the marking relays of each group and carried over series connected back contacts of the group relays of all relay groups connected between the group in question and the source of current, each marking relay being adapted upon

energizing to connect itself into the holding circuit of its group.

8. In means for effecting the successive connection of simultaneously calling telephone lines, the combination of a number of lines, a number of relays adapted to mark corresponding lines as calling, the lines and relays being divided into a plurality of groups, a group relay allotted to each group and adapted to operate upon a call occurring in its group, a source of current and a holding circuit common to all the marking relays of each group and carried over series con-

nected back contacts of the group relays of all relay groups connected between the 15 group in question and the source of current, each marking relay being adapted upon energizing to connect itself into the holding circuit of its group, the group relays being included in the corresponding holding circuits. 20

In testimony that we claim the foregoing as our invention we have signed our names this 28th day of October, 1920.

GOTTHILF ANSGARIUS BETULANDER.
